WINDOW CHANNEL STRUCTURE
Benedict R. Gerulis, 6517 37th Ave. N.,
Minneapolis 27, Minn.
Filed Aug. 29, 1963, Ser. No. 305,428
1 Claim. (Cl. 20—52)

This invention relates to a new and useful improvement in a window channel or sash guide structure.

It is an object of this invention to provide a simple construction of a sash guide structure which can be easily and quickly assembled and which can be readily and accurately inserted within a window frame with no particularly skilled labor being required.

It is also an object of this invention to provide a sash guide structure which is substantially non-conductive of heat or cold and which forms of itself in connection with the associated sash an effective weather seal.

It is also an object of this invention to provide a sash guide structure which has a substantially frictionless and freely slidable surface to accommodate the associated sash.

It is more specifically an object of this invention to provide a sash guide structure comprising a spring loaded removable self-retaining backing plate yieldingly urging said sash guide structure into an operative relationship with the associated sash.

These and other objects and advantages of the invention will be fully set forth in the following description made in connection with the accompanying drawings in which like reference characters refer to similar parts throughout the several views and in which:

FIG. 1 is a fragmentary view in side elevation on a reduced scale of the inside of a wall having a window construction embodying the invention;

FIG. 2 is a view in vertical section taken on line 2—2 of FIG. 1 as indicated;

FIG. 3 is a fragmentary view in horizontal section on an enlarged scale taken on line 3—3 of FIG. 1 as indicated;

FIG. 4 is a fragmentary view on an enlarged scale in vertical section showing a detail of applicant's invention;

FIG. 5 is a broken view in perspective showing applicant's invention;

FIG. 6 is an exploded view in horizontal section showing parts of applicant's invention;

FIG. 7 is a view similar to FIG. 6 showing parts of applicant's invention in partially assembled condition; and

FIG. 8 is a view similar to FIG. 6 showing applicant's invention in assembled condition.

With reference to the drawings, and more particularly with reference to FIGS. 1-3, a window construction of conventional design is indicated comprising a window frame 10 having a header 12, a sill 13, and side rails or jambs 14, with only one of said side rails being here shown. An outer stop strip 16 extends about the top and sides of the frame at the outer face thereof and an inner composite stop strip 17 extends around the top and sides of the inner face of said frame comprising a plain strip 18 and an overlying decorative molding strip 19.

Slidably carried in said frame is an upper sash 23 having a top rail 24 and oppositely disposed stiles 25, and a lower sash 28 comprising a bottom rail 29, oppositely disposed stiles 30, and the meeting rails of said sash 23 and 28 are indicated by the character 32. Said window frame is shown in FIG. 1 with an inner facing molding or trim strip 33 at the top and sides thereof.

With reference to FIG. 3, it is seen that the stop strips 16 and 17 and the side rail 14 define a vertical sash channel 35. Disposed in said channel 35 is applicant's novel window channel or sash guide member 39. It is to

2

be understood that said sash channel is present at either inner side of said window frame with applicant's sash guide member being installed in each of said channels and that the construction of either side of said window frame is a counterpart of the other side. The structure at only one side of said window frame is here illustrated and described.

The view in FIG. 2 indicating the installation of applicant's window guide 39 shows a rear view thereof. Applicant's window guide member will be of a length to correspond to the length of any given window channel.

With reference to FIG. 5, applicant's window guide member 39 comprises a channel member 40 formed of a suitable material. It has been found that one desirable form of such material is polyvinyl chloride and that applicant's guide member may be readily formed of this material as an extrusion. Said member will have some degree of flexibility yielding to transverse and longitudinal stress. The material provides a good sliding substantially friction free surface and is sufficiently non-conductive to form a good insulating material and thus provides a self-forming weather seal in connection with the sash associated therewith.

The member 40 comprises a central web or plate-like bridge member 42 having sash guide channel portions 43 and 44 at either side thereof, said channel portions here being shown at substantially rectangular in cross section. Said channel portions comprise forwardly facing sides 45 and 46, rearward sides 47 and 48, adjacent inward sides 49 and 50 and remote outer sides 51 and 52. Said forwardly facing sides 45 and 46 are respectively spaced from said side walls 49 and 52 to form slots 54 and 55 therebetween, with said slots opening into the passages 56 and 57 respectively formed within said channels and extending the full lengths thereof. Extending outwardly of the outer walls 51 and 52 at right angles thereto are flange portions 59 and 60 having right-angled rearwardly extending sides 61 and 62 parallel to one another and adapted to be seated within and bear against the adjacent side walls of the window channel 35, as indicated in FIG. 3.

The rear sides 47 and 48 of said channel portions 43 and 44 extend outwardly sidewise in the plane of said rear sides to form flange portions 65 and 66.

Said web portion 42 is positioned substantially centrally of the depth of said side walls 49 and 50. Said channel portions 43 and 44 with their respective slots 54 and 55 form the forwardly facing portion of the channel member 40.

A backing pressure plate member 70 is removably secured to the rearward facing portion of said channel member 40 overlying the same. Said backing plate will be formed to have a slightly concaved central longitudinal portion 71, and extending outwardly thereof are angled wing-like side portions 73 and 74 having an angular cross sectional relationship therewith and having inwardly turned free end portions 75 and 76 respectively forming finger-like flange portions.

The respective lines of juncture of said wing-like portions 73 and 74 and the central portion 71 are well rounded to form bead-like outward projections 78 and 79. At the free ends of said wing-like portions 73 and 74 there will be a spread or width somewhat less than the width or distance between the free edges of the flange portions 65 and 66. Said backing plate member 70 will be formed of a suitable material such as of sheet metal which will have a spring-like or resilient quality resisting the spread of said wing-like portions 73 and 74.

Said web 42 will have longitudinally spaced apertured relatively small recessed cup-like portions 82 through which will extend screws 83 with the heads thereof being

seated within said recessed portions. In alignment with each of said apertures and having said screws extending axially therethrough are tapered coil springs 85 seated against the inner side of said web at one end thereof and bearing against the adjacent surface of said plate member 70 in operating position, as indicated in FIG. 3. Said screws will extend through said plate member 70 through apertures 88 therein positioned to accommodate said screws.

Disposed in said passages 56 and 57 are sash balancing springs 91 which will be secured to the upper end portions of the rear sides 47 and 48 by terminal hook-like portions of said spring which is a conventional design for securing said springs and is not here illustrated. The lower ends of said springs 91 will be equipped with sash engaging hook like members 92 which will be seated in accommodating recessed portions formed in the bottom edge portion of the respective sash. The sash balancing elements comprising the springs 91 and hooks 92 here illustrated are not intended to represent any patentable novelty but are merely intended to be of a conventional design and are included to show applicant's device as a fully operative structure.

With reference to FIG. 3, it is noted that the stiles 25 and 30 of the sash 23 and 28 at their outer sides are provided with grooves 26 and 31 to receive therein the forward projections of the channel portions 43 and 44.

Operation

Applicant's sash guide member 39 as an integral unit is installed within the sash channels at either inner side of a window frame structure. The unit is placed in the sash channel 35 and is secured therein by the screws 83. The width of the sash guide member is in accordance with a standard dimension as to width for sash channels, hence there is no fitting requirement for this installation and there is thus no need for the application of particularly skilled labor. The screws 83 readily adjust the degree of tension desired between the sash guide member and the associated sash to provide a smooth operation in raising or lowering the sash. There will be sufficient yielding in the pressure exerted by the sash guide member to avoid any binding of the sash.

As to the construction of applicant's sash guide member 39, the channel portion 40 thereof is formed as a unitary extrusion in accordance with the specification of sash channels in window frames. The unit as a whole is readily assembled with the backing plate member 70 being positioned by a snapping or springing action, as illustrated in FIGS. 6-8, with the coil springs 85 first having been positioned upstanding from the rear side of the web portion 42.

The wing-like portions 73 and 74 together with the central portion 70 of the backing plate form a spring-like member. The wing portions must be spread, as illustrated, to embrace the flanges 65 and 66, and thus said flanges are engaged by said finger-like portions under tension. Said finger-like portions overlap the inner sides of said flanges sufficiently to provide for substantial flexing action without becoming disengaged therefrom.

It will be understood that the apertured recesses 82 in the web 42 are formed after the guide member 40 has been extruded and also at such time will be cut into desired lengths. The backing plate will have the apertures 82 appropriately formed therein.

As illustrated in FIG. 3, the projections of the channel portions 43 and 44 fit very nicely into the accommodating grooves of the associated sash. There will be sufficient

pressure exerted by the backing pressure plate and the springs 85 to form a very effective weather seal in connection with the sash. It is to be understood that the use of springs though desirable, is not essential. The pressure exerted will be adjusted to permit a ready raising or lowering of the sash.

The specific sash balancing elements shown indicate a conventional design. These elements are installed at the point of manufacture and assembly are here included merely to present a complete sash guide member and not to indicate a particular element of novelty.

The essential elements of patentable novelty that provide new and useful improvement are found in the spring-like backing plate having removable self engagement with the guide member portion of applicant's invention so that there is a very easy time-saving assembly of applicant's total structure. Further, with applicant's invention completely assembled at its point of manufacture, it is very readily and quickly installed as an assembled unit within a window frame structure assuring an arcuate fit into the window channel and with the associated sash.

Thus the applicant has provided a very simply constructed and simply assembled sash guide structure which is adapted for ready and accurate installation. This invention has proved to be very successful in commercial use.

It will of course be understood that various changes may be made in the form, details, arrangement and proportions of the parts, without departing from the scope of applicant's invention which, generally stated, consists in a structure capable of carrying out the objects above set forth, in the parts and combinations of parts disclosed and defined in the appended claim.

What is claimed is:

35 A sash guide structure having in combination, an elongated sash guide member comprising a pair of spaced channel portions having a connecting web therebetween and having extended frame portions at the remote sides thereof to engage the side walls of a window channel,

40 said channel portions being substantially rectangular in cross section, coplanar oppositely extending flange portions formed as transverse projections of the rear walls of said channel portions and having a span less than the span of said extended frame portions, and

45 a spring-like backing plate member extending longitudinally of said guide member overlying a substantial central portion of the rear side thereof, said plate member comprising a central longitudinal portion and side portions at either side thereof having a wing-like cross sectional relationship therewith, inwardly turned finger-like flange portions at the free ends of said side portions, said free ends being spaced apart a distance less than the span of said coplanar flange portions whereby said finger-like flange portions in being spread by pressure against the back of said coplanar flange portions engage and embrace said flange portions under tension.
